Primary Examiner—Stella Reid

Attorney, Agent, or Firm—Haugen and Nikolai

[57] CLAIM

The ornamental design for an examination table, as shown and described.

DESCRIPTION

FIG. 1 is a left side elevational view of an examination table, showing my new design;

FIG. 2 is a right side elevational view thereof;

FIG. 3 is a front elevational view thereof;

FIG. 4 is a rear elevational view thereof; and,

FIG. 5 is a top plan view thereof.

The bottom of the article is substantially plain and unornamented.
